COLLAPSIBLE MANDREL FOR SMALL-MOUTHED CONTAINERS

Irving F. Mandell, New Rochelle, N. Y., assignor to Reinforced Paper Bottle Corporation, New York, N. Y., a corporation of Delaware

Application October 24, 1938, Serial No. 236,820

11 Claims.

(Cl. 93—59)

This invention relates to mechanical devices adapted for use as abutment mandrels or formers in setting the bottoms of hollow bodies firmly in their bases.

In the construction of containers having a thin wall of paper, metal, or other sheet material, whether cylindrical, polygonal, conical or conventionally bottle shaped, particularly such as have contracted openings for filling and discharging contents, it becomes necessary to insert and secure a bottom closure and effect an impervious, essentially firm joint.

To accomplish this purpose it is properly regarded as essential that a rigid backing element, which may be considered as a mandrel, be entered a predetermined distance within the body, against the outer face of which the bottom closure rests, retaining the closure in its proper position during its fixation and capable of resisting any impacting force at its margin, while coincidentally maintaining the shape and size of the container in a positively accurate manner.

While this can be easily done if the area at the open end of the container equals, or exceeds, that of the end in which the closure is secured, when the open end is reduced in area it presents very considerable difficulties, materially increasing if the areas at the ends of the container body are unlike and proportionately to such variation.

A metal mandrel capable of passing through the small mouth of a container, thereafter expanding to the full diameter of its body, is a desideratum, even an actual necessity, in the manufacture of certain types of containers and has been regarded as impossible to attain.

Having this matter in mind, it is an object of the present invention to provide a collapsible mandrel, which in its normal contracted condition, is readily entered into a container body through its small mouth, thereafter expanded to its predetermined limit, which equals the area of the body at the point of insertion of the bottom closure, and may be approximately twice the diameter of its mouth.

A further feature is in the provision of an expansible anvil which presents a substantially unbroken ring to the interior of the container when expanded, its flat face seating the closure in its adjusted position, and which may be instantly entered and retracted automatically in connection with the closure setting mechanism.

These important objects are accomplished by the novel construction and combination of parts hereinafter described and shown in the accom-

panying drawings, forming a material component of this disclosure, and in which:

Figure 1 is a side elevational view of an embodiment of the invention as in operative position within a container shown in broken lines. 5

Figure 2 is a front elevational view of the mandrel.

Figure 3 is a side view of the same shown in contracted position, as in emerging from a container. 10

Figure 4 is a partial sectional view of the head in operative position.

Figure 5 is a similar view of the same parts in collapsed position.

Figure 6 is a side elevational view partly in section, showing a modified form in extended position. 15

Figure 7 is a front end elevational view of the same.

Figure 8 is a side elevational view, partially in section of the modified form in operative position. 20

Referring in further detail to the drawings, the numeral 15 designates a cylindrical sleeve of such diameter as to readily enter the mouth of a 25 container in which a bottom closure is to be set, the container being indicated by broken lines in Figures 1 and 3.

The sleeve 15 has a reduced outer end 16, suited to fit a rigid support, part of the machine in 30 which the container is constructed, and held firmly therein by the threads 17.

In the front of the sleeve is an enlarged bore 18 receptive of a tight fitted bushing 19, its outwardly extending enlarged portion 20 uniform in 35 diameter with the sleeve 15.

Mounted slidably in the sleeve and bushing is a spindle or cam rod 22, moved by mechanism connected to its threaded rear end 23.

The extending front end of the spindle has 40 fixed upon it a collar 24, tapered at its overhanging hollow forward end 25 and provided with a plurality of longitudinal slots 26 in its periphery, the forward edge bevelled as indicated at 27, to present a cam surface.

The front enlarged end 20 of the bushing is similarly provided with spaced slots 28, six being shown, aligned with the slots 26, and close fitted to them are finger bars 39, their rear ends held within the slots by pivot pins 31. 45

The lever-like bars 30 are rounded at their outer edges, so that when infolded as to agree with the radius of the sleeve 15 and bushing 20.

On the inner side edges of each of the finger bars 30, at their rear extremities, are inreaching 50

55

projections 32 suited to engage in grooves 33 formed in the front portions of the spindle 22 and arranged in such manner as to constitute stops limiting the out-turning movement of the bars.

The forward curved ends 33A, of the grooves 33, serve as contactual surfaces co-acting with the rounded forward portions 32A of the projections 32 of the bar 30, during in-turning and out-turning movements of the bars.

Also on the underside of the bars, at points in advance of the pivots, are inreaching cam lugs 35 having angular rear edges suited to contact the bevelled cam 27 at the front of the collar 24, and by it become raised or outturned, as best shown in Figure 4, the lower edge 36 being laterally bevelled and adapted to rest on the bottom of the slots 26 when the spindle 22 is moved forwardly relative to the sleeve 15.

It is important in the operation of this collapsible mandrel, because of its relation to the machine, that the bars 30, with all their associated parts, shall be fully controlled during the complete action of their in-turning and out-turning, with no appreciable looseness, back-lash, or uncontrolled movement.

Thus, when the spindle 22 is drawn rearwardly, the forward, curved portion 33A, of the groove 33, contacts the rounded forward portion 32A, of the lug 32 on the bar 30, to effect the in-turning movement of the bar; coincidently the angular rear edge and rounded corners 35A of the lug 35, contact with limited clearance, the corner 27A, between the cam surface 27 and bottom of the slot 26 to maintain full and positive control of the bars 30.

The extreme front ends of the bars 30 are offset towards the inner edges, presenting lugs 38 extending outwardly and are drilled to receive pivot pins 39 passed through flanges 40-41 reaching rearwardly from the central back portions of curved plates 42, and by which they are hingedly attached to the finger bars.

The plates 42 present flat front faces and arcuate outer edges 44, their radii conforming to the inner diameter of the container.

The end edges of the plates, which are a series of segments capable of forming a complete circular seat on the marginal portion of the container 50 bottom closure, are cut radially with the axis of the circle and furthermore, these end edges 45 are formed angularly so that one overlaps the next adjacent, thus completing a substantially unbroken circle, by reason of their close contact, 55 the bevelled edges permitting the plates to swing clear and free during the inward movement of the bars and entire segmental plate group.

Each of these segmental plates 42 have extending from their rear inner surface, offset from, and 60 to one side of the center of their length, a lug 46 drilled to receive hooks formed at the outer ends of wire rods 48, which have similar hooks at their opposite ends engaged in corresponding openings in the thin, forwardly projecting end 65 25 of the collar 24, but offset so that the rods extend at a definite oblique angle, tangential to the axis of the device.

From the foregoing it will be understood that when the spindle 22 is drawn rearwardly with 70 reference to the sleeve 15, the plates 42 are turned on their hinged connections with the finger bars 30, into a substantially lengthwise position, all parts being closely folded within an area essentially equivalent to that of the sleeve.

Conversely, when the spindle is projected for-

wardly, the several bars 30 are moved outwardly into an angular position, and coincidently, the plates 42 are turned to present a firm flat faced seat to contact the closure element, while at the same time, the periphery of the ring, formed by the segments, is pressed firmly and uniformly into contact with the interior of the container, there held within the machine collar or holder encompassing it.

In the modification shown in Figures 6, 7, and 10 8, an essentially similar rigid sleeve 50 has slidably mounted in its a spindle 51 having at its extending front end three bevelled cam faces 52.

The sleeve is slotted at its forwardly projecting end, as at 53, and pivoted on pins 54 are lever 15 arms 55 their rear ends 56 curved downwardly and inwardly to engage within corresponding recesses 57 in the spindle 51.

Adjacently in front of the pivots 54, the levers are each provided with an inreaching lug 58 having a bevelled cam face at its under edge to contact the cams 52 when the spindle is moving lengthwise relative to the sleeve.

The outer ends 60 of the lever arms 55 are hingedly engaged by pins 61, with interengaged elements 62-63 reaching rearwardly from pairs of opposed arcuate plates 64-65 which, upon being fully extended, as shown in Figures 6 and 7, complete a circular formation; these plates are formed radially at their end edges and constitute 30 segments.

Pairs of lugs 66-69 extend from the rear of the plates 64-65, these lugs being receptive of studs 70-71, to which are connected links 72-73, in turn pivotally connected at their opposite ends with studs 74 set in heads 75 of bars 76, having inturned rear portions 77 connected by pivot pins 78 in grooves 79 formed in the spindle 51.

The elements 68 to 75 inclusive form, in effect, universal joints and are operated in such manner that when the spindle 51 is retracted, or drawn outwardly, with respect to the enveloping sleeve 50, as to cause the plates 65-65 to pivot on the axes 61 and fold inwardly toward each other, so that when withdrawn by action of the lever arms 55, as to be within the compass of the sleeve 50.

Although the foregoing is generally descriptive of the best known embodiments of the invention, it is to be understood that minor changes may be made within the scope of the appended claims.

Having thus described the invention, what is claimed as new, and sought to secure by Letters Patent is:

1. A closure setting device for the bottoms of containers, comprising a rigid support enterable through the smaller end of the container, and an expandible head carried by said support to abut the bottom closure unyieldingly along its entire marginal area and at a spaced distance within the larger end of the container.

2. A closure setting device for small-mouthed containers, comprising a rigid support enterable through the smaller end of the container and an expandible head composed of swinging segmental plates carried by radially movable arms in said support to abut a closure entered within the larger end of the container to a predetermined distance.

3. A collapsible mandrel comprising a dilatable head, a fixed tubular support extending axially from said head, a spindle slideable in said support, and means actuated by said spindle, when moved relative to said support, to open and close said head to a predetermined limit, said head when 75

- dilated presenting a flat substantially unbroken outer surface.
4. A collapsible mandrel for container bottom closure insertions, comprising a sectional ring on which the closure seats, said ring contacting the interior of the container when expanded and limiting the insertion of the closure, and means for opening and closing the sections of said ring.
5. In a collapsible mandrel, a head comprising a series of segmental plates having overlapping bevelled ends and arcuate peripheries forming a complete circle when expanded, and a corresponding series of movable arms, said plates pivoted on transverse axes on said movable arms to fold into positions angularly disposed to said arms when said head is contracted.
6. In a collapsible mandrel, a head comprising a sectional ring composed of segmental plates, lever bars to which said plates are hingedly connected, means to fold said bars longitudinally, means to distend said bars angularly outward, and means to turn said plates into different angular positions in accordance with the position of said bars.
7. A collapsible mandrel for container bottom closure insertions, comprising a sectional ring on which the closure seats, said ring contacting the interior of the container when expanded, means to open and close the ring sections, and a rigid support for said ring enterable through the lesser opening in the opposite end of the container.
8. A collapsible mandrel having an expandable head, comprising a sleeve, a spindle therein, lever bars pivoted in said sleeve, co-operative cams on said spindle and bars to move the bars outwardly when said spindle is projected relative to the sleeve, said bars moved inwardly upon a reverse motion, segmental plates so connected to said bars as to form a flat face having a circular periphery when said bars are moved outwardly, and means to turn said plates through an angle of approximately ninety degrees when said bars are collapsed.
9. A collapsible mandrel having an expandable head, comprising a sleeve, a series of lever bars pivoted at one end of said sleeve, segmented plates hinged to the free forward ends of said bars, a spindle slideable in said sleeve and having grooves to receive the rear ends of said bar, a plurally grooved cam collar fixed on the front end of said spindle, cam lugs on said bars co-operative with said collar, and connections between said collar and plates whereby the plates are turned uniformly at right angles to the plane of said mandrel when said spindle is in a forward position and approximately parallel thereto when the spindle is moved rearwardly.
10. A collapsible mandrel having an expandable head, comprising a sleeve, a series of lever bars pivoted at one end of said sleeve, segmental plates hinged to the free forward end of said bars, a spindle slideable in said sleeve and having grooves to receive the rear ends of said bar, a plurally grooved collar fixed on the front end of said spindle, a cam combined therewith, cam lugs on said bars co-operative with said cam, and links connecting one end of each plate with said collar, said links disposed at oblique angles to said bars and operative to tilt said plates into substantially parallel positions upon rearward movement of said spindle and into a uniform level plane upon forward movement of the spindle.
11. A collapsible mandrel having an expandable head, comprising a sleeve, a series of lever bars pivoted at one end of said sleeve, segmental plates hinged to the free forward ends of said bars, said plates being in two equal sections hinged at their median line, a spindle slideable in said sleeve, cams on the forward end of said spindle engageable with said bars, said cams causing spreading of the bars when the spindle is advanced, hinged connections between said plates and bars, yokes connecting the adjacent ends of the plate sections, and connections from said yokes and said spindle whereby the plates are turned into substantially parallel positions upon retraction of the spindle and present flat level faces upon moving said spindle forwardly to form a flat faced ring, said plates when folded parallel being within a circle of no greater diameter than that of said sleeve.

IRVING F. MANDELL.
